ATTORNEY

UNITED STATES PATENT OFFICE.

GEORGE W. TROOP, OF GENEVA, OHIO.

BELT BUCKLE.

Application filed August 13, 1923. Serial No. 657,080.

My invention relates to belt buckles and especially to buckles whereby both ends of the belt may be held in detachable engagement therewith without puncturing the belt.

5 My buckle structure is especially suitable for use with belts of some form of rubber composition, though it may be used with belts of any composition having adequate resiliency, even of various kinds of leather

10 or textile material.

It is a special object of my improved buckle to provide for ready manipulation thereof in adjusting either end of the belt, and to do this with a minimum number of 15 parts, thus tending to simplicity of construction and low cost of manufacture.

It is a further object of my new and improved buckle to provide such structure that possesses great ease of clamping and releasing 20 either end of the belt, whose pivotal parts may be readily manipulated through the intermediacy of the straps without direct manual contact with the clamping parts of the buckle, and which notwithstanding such 25 ease of movement, presents great certainty of action and positive control in either release or adjustment.

With these and other objects in view, I have described the detailed structure in the 30 following specification, recited it in the appended claims and illustrated it in the accompanying drawings in which

Figure 1 is a plan view of my improved buckle with a belt in position therein;

35 Figure 2 is a longitudinal section taken on the line 2—2 of Fig. 1;

Figure 3 is a similar view but showing the parts partly disengaged, and

40 Figure 4 is an inverted plan view of the buckle only.

In the drawings in which similar reference characters indicate like parts throughout the several views, A designates the main frame part of my buckle which is shown applied to a belt having the usually-fixed 45 end D and overlapping end E, B the clamping member hinged to A, and C the loop member which in my buckle is itself hinged to the clamp member B.

50 The main frame part A comprises the front plate portion 10, side flanges 11, a transverse bar 12 which is spaced from the front plate by a relatively broad slot 13, the latter having slightly extended portions 22.

55 Flanges 11 have somewhat enlarged portions or lugs 23 for mounting the part B thereon.

The clamping member B comprises the cam toe 17 for engaging the permanent end D of the strap or belt and is shown in Fig. 4 as having clamping teeth 18 for engaging 60 the belt end, a bent part 16 integral with 17, and a reduced central portion 21 cut away from the main end 16, as shown at 24 in Fig. 4, and looped upon itself to form an eye for hinged engagement with the loop 65 member C. The member B is hinged to the lugs 23 by means of lateral extensions 25 integral with part B and pivoted in apertures 26 in said lugs. Beyond the loop 21 is an extension 27 which serves to avoid rocking 70 of part B too far, by contact thereof with the plate 10.

The loop member C comprises the plate 14, an end transverse bar 20 spaced from 14 by a slot 19 of adequate width to permit insertion of the belt therethrough, a cut-out central portion 28 to receive loosely therein the loop 21, but having integral therewith inwardly extending lugs 15 which are received in the ends of said loop 21, thereby 80 hinging C to B.

The operation of my new and improved belt buckle will now be explained. It is a decided and positive advantage of my structure that the greater the strain on the ends 85 of the belt when my buckle is applied thereto, the tighter and more secure becomes the attachment therein, and yet this does not diminish in any way the ease with which the parts may be released. This will appear as 90 the operation is shown. To attach the fixed end to the buckle, the tip E of the belt is first threaded through 19, as shown in Fig. 3, or the part 20 may be directly grasped manually, as it will be seen that the latter 95 part is always in some position to be readily grasped without picking the same out of contact with another plate. If the belt is in the slot 19, pulling the belt in the doubled relation shown in Fig. 3, downward, will release both parts C and B which will then swing together on the pivots 25, the teeth 18 then swinging to the right in Fig. 3 and permitting the insertion of the end D of the belt between the parts 10 and 17. It will be 100 noted that releasing 20 and C may also release 27 from the plate 10.

While holding parts A and 12 in the left hand, parts 20, 14 and B may be manipulated with the right to lock the parts 17 110 and 18 into engagement with the belt end D, as shown in Fig. 3. The last step in attach-

ing the buckle, is to thread the tip end E of the belt through slot 19, if it has not already been done, pass it over the face of the plate 10 and through the slot 13, when the parts 5 will be attached securely, as shown in Fig. 2. The stationary end of the belt D cannot become loosened without swinging 17 and 18 on their pivots 25, and the constant stress on the belt loop D E passing through 19 pulls in that direction upon part 16 of B to prevent such loosening. Friction on bars 12 and 20, the latter binding upon the end of 10 holds end E to the main part A of the buckle. Part 27 also prevents rotation of 15 B in the other direction. So all parts are well held in clamped position as long as any strain whatever is exerted outward upon the belt and buckle. The belt end need be released from but one bar —12— to open the 20 buckle, since part C is ready to swing open whenever inner pressure is withdrawn from it. Thus an inner force exerted upon the loop or bar 20 directly or by the belt may be employed to readily release not only the tip 25 end but the stationary end also of the belt from the buckle.

I do not desire to limit myself to the exact details of my improved buckle an embodiment of which is here shown, but I expressly 30 reserve all protection properly accruing under the doctrine of equivalents.

What I claim and desire to secure by Letters Patent is—

1. A belt buckle comprising a flanged 35 front plate, a clamping member pivoted to the flanges, a loop element pivoted to said clamping member for actuating the latter, the said loop element being movable toward and from said front plate and itself comprising a plate and a transverse bar connected with the plate at its ends and spaced from said plate intermediate the ends, the 40 said bar being bent outwardly from the loop plate in a direction toward the said front

plate, and the transverse bar being sufficiently spaced from the outer end of the front plate when the buckle is in closed position, to permit a belt being inserted through the space between the said bar and said outer end, and the space between the bar and the 50 loop plate. 45

2. A belt buckle comprising a main frame member having a front plate and a transverse bar spaced from one end thereof for receiving the free end of a belt through such 55 space, a swinging member mounted upon the inside of said plate and having means for engaging the stationary end of a belt, means comprising a part pivoted to said swinging member for actuating the latter, 60 and a transverse bar extending in overlapping and spaced relation to the other end of said front plate whereby the insertion of the free end of the belt through the spaces adjacent both said bars and over the plate will 65 clamp said free end in adjusted position and thereby hold the swinging member in positive engagement with the stationary end of the belt.

3. A buckle comprising a front plate, side 70 flanges integral therewith, and a spaced bar at one end thereof, a clamping member pivoted on said flanges and having means at one end for engaging the belt, hinge means adjacent the opposite end, and an extension element beyond the hinge means for contacting the said plate to limit the swinging movement of the engaging means, and a loop element connected to said hinge 75 means upon said clamping member including a plate member and a bar spaced therefrom overlapping the opposite end of the front plate when the buckle is closed, but sufficiently spaced therefrom to receive a belt therebetween. 80

In testimony whereof I hereunto affix my signature.

GEORGE W. TROOP.
